DIRT TAMPER OR THE LIKE

Orin N. Cooper, Garwin, Iowa

Application November 13, 1957, Serial No. 48,433

Term of patent 14 years

(Cl. D55—1)

Fig. 1 is a top plan view of a dirt tamper or the like showing my new design;

Fig. 2 is a rear elevational view thereof;

Fig. 3 is a front elevational view thereof;

Fig. 4 is a side elevational view thereof; and

Fig. 5 is a sectional view thereof taken along line 5—5 in Fig. 2.

The dominant features of my design reside in the portions shown in full lines.

The handle is shown as broken away in part for convenience of illustration only.

I claim:

The ornamental design for a dirt tamper or the like, substantially as shown and described.
